ICE AUGER

Uuno Rantanen, Rauhankatu 2-4 A 5,
Heinola, Finland

Filed Sept. 11, 1974, Ser. No. 504,883

Claims priority, application Finland Apr. 26, 1974

Term of patent 14 years

Int. Cl. D8—01

U.S. Cl. D8—8

Fig. 1

Fig. 2

FIG. 1 is an elevational view of an ice auger embodying my new design, the opposite side to that shown in FIG. 1 is substantially a mirror image of the side shown.

FIG. 2 is a similar view of the ice auger in folded position.

I claim:

The ornamental design for an ice auger, as shown and described.
